UNITED STATES PATENT OFFICE.

JOHN MILLENDER BYRD, OF HAZLEHURST, GEORGIA.

TURPENTINE-CUP.

1,121,472.

Specification of Letters Patent. Patented Dec. 15, 1914.

Application filed July 15, 1910. Serial No. 572,198.

To all whom it may concern:

Be it known that I, JOHN MILLENDER BYRD, a citizen of the United States, residing at Hazlehurst, in the county of Jeff 5 Davis and State of Georgia, have invented certain new and useful Improvements in Turpentine-Cups; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to improvements in sap receiving receptacles, such, for instance, as are commonly employed to receive crude turpentine as it runs from the tree. These 20 receptacles, as is well known, comprise an apron which is secured to the tree and a cup or box into which the flowing sap is deflected by the apron. Various forms of cups have been designed but in every instance, 25 their practical value has been materially reduced or rendered negligible by some peculiar or distinctive feature of construction.

A receptacle according to the present invention, embodies as heretofore the apron 30 and the cup but these parts are of such construction and association that the various objectionable features which are inherent in the prior constructions are avoided and the resultant structure is one which is es- 35 sentially practical and inexpensive and which has a greatly superior degree of utility.

The novel features of construction and association which characterize the present 40 improvement will be pointed out succinctly in the detailed description which follows.

The invention is illustrated in the accompanying drawings wherein;

Figure 1 is a view showing the improved 45 receptacle applied to a tree; Fig. 2 is an enlarged perspective view of the receptacle; Fig. 3 is a developed plan view of the blank from which the receptacle is formed; Fig. 4 is a vertical section taken through the 50 transverse center of the cup or box.

Similar characters of reference designate corresponding parts throughout the several views.

The improved receptacle is constructed of 55 sheet metal and its parts are preferably integral.

The apron is designated generally by the numeral 1 and the cup or box is designated generally by the numeral 2. Said cup or box comprises the front and back walls 3 and 4, and a connecting web 5 which forms both the bottom and end walls. The walls 3 and 4 are perfectly flat and are disposed in parallel relation so that the distance between them is the same at all points. These 60 walls are moreover of approximate though not quite true semi-disk shape, their upper edges being straight and their under edges curved. The web 5 joins the curved under edges of the walls 3 and 4 and has the same 65 contour. This contour is such that the central portion of said web as 5^a which forms the bottom of the cup, is of concave outline, while the end portions of said web as 5^b, which form the end walls of the cup are 70 straight, so that the cup in longitudinal section defines an arc of a circle having divergent tangent lines, the arc portion forming the bottom of the cup and the diverging tangent portion forming the end walls of 75 the cup. These straight end portions 5^b merge gradually with the central portion 5^a and extend upwardly from the latter in divergent relation, their upper edges being 80 flush with the upper edges of the walls 3 and 4 and together with the latter defining 85 the open rectangular mouth of the cup.

The apron 1 is of substantially rectangular outline and it extends upwardly and rearwardly from the wall 4 at an angle of 90 about 35°. Said apron is permanently joined to the upper edge of the wall 4, the meeting lower edge of the apron and upper edge of said wall defining a straight line. The apron is moreover co-extensive in 95 length at all points with the upper edge of the wall 4. Hence the end edges of the apron are parallel. These parallel end edges are provided with upwardly directed parallel flanges 6 which are curved in cross 100 section and which extend to the aforesaid rectangular mouth of the cup. These flanges, however, terminate short of the rear edge portion of the apron so that corner shoulders, as 7, are formed. The projecting 105 rear edge portion affords a projecting lip, as 8, which efficiently engages in the kerf made in the tree.

The manner in which the cup is fitted to the tree is shown in Fig. 1. The lip 8 is 110 engaged in the kerf and a nail or other fastening device is driven through the apron

at a central point in order that the attachment of the receptacle may be of positive nature. The sap which runs from the tree is deflected by the apron into the cup in the well known manner. The practical efficiency of the device accrues from the combined relation of the following advantages.

Owing to the permanent association of the apron and the cup the latter can never be displaced from the former and the removal of the receptacle for "dipping" is unnecessary. By reason of the permanent association of the parts referred to coupled with the corner shoulders 7 which engage against the tree at both ends of the cup, the latter remains in its proper position, under all conditions and cannot, by accident or by the rubbing of animals be moved in any direction. Owing to the fact that the apron is co-extensive in length at all points with the length of the mouth of the cup coupled with the provision of the flanges 6 all of the sap which flows upon the upper portion of the apron is deflected by the latter; there is no waste and the sap flows in a straight uninterrupted path. The flat form of the rear wall 4 adapts the device to trees of different diameter and degrees of curvature and the relation of the apron to this rear wall is such that the cup is caused to hug the tree. This fact coupled with the fact that the flanges 6 extend continuously between the tree and the cup, renders it impossible for any sap to escape around or under the flanges of the cup or to enter between the latter and the tree. Owing to the fact that the walls 3 and 4 are flat and parallel either a right or left hand dipper may be used. Moreover the form of these walls coupled with the form and relation of the web 5 assures that all of the turpentine may be removed and that movement of the dipper is effected with as little friction as possible. The curved cross sectional form of the flanges 6 provides for a ready cleaning of the gutters afforded by said flanges.

The relation and form of the parts are of such nature that they may be made integral and that the device may be stamped from sheet metal. The blank from which the device is stamped is shown in Fig. 3 wherein the lines 10 define the adjoining edges of the web 5 and the walls 3 and 4; the line 11, defines the adjoining edges of the wall 4 and the apron 1 and the lines 12 and 13, together with the parts of the lines 10 which adjoin the lines 12, define portions as 14 which are folded in overlapping relation against the outer faces of the portions 5^b of the web 5 and which materially strengthen the cup as well as its connection with the walls 3 and 4.

The receptacle, being made of sheet metal, and embodying no separable or extraneous parts is not affected by weather conditions,

and requires no especial care in handling or shipping.

To summarize, the parallel flanges of the apron curved in cross section throughout their length permit a straight, free flow of 70 the turpentine from the tree to the box and by reason of the cross section curvature avoid the formation of an acute angle between the flanges and shelf of the apron for the lodgment and caking of the turpentine when stiff and thick in the early spring and late fall of the year. By forming the body of the box or cup as described so as to define in longitudinal section an arc of a circle having divergent tangent lines, the 80 end walls are straight divergent walls merging at the lower ends into a concave bottom so that there is formed for the turpentine a receptacle in which the sweep of the turpentine dipper at the bottom of the receptacle 85 is short and in the arc of a circle while the sweep at both ends is straight and at a relatively sharp angle and this gives the advantage of less friction between the dipper and walls of the receptacle and the removal of 90 the turpentine with greater ease and more effectively because the space at the bottom for the turpentine to settle or fall back is reduced to the minimum.

Having fully described my invention and 95 set forth its merits, what I claim is:

1. A receptacle of the type set forth comprising a cup which embodies flat parallel front and rear walls having curved under edges and a connecting web joined to said edges, conforming to the curvature thereof, and forming the bottom and end walls of the cup, and an apron which projects rearwardly and upwardly from the upper edge of the rear wall, the apron being of rectangular form and being at all points co-extensive in length with the length of the mouth of the cup defined by the upper edges of said front and rear walls and said web, the apron being furthermore permanently joined to the rear wall and having at its ends parallel upturned flanges which extend continuously from the said mouth to the tree upon which the receptacle is secured and curved in cross-section beginning at the rear side wall of the cup and continuing rearwardly throughout their length, substantially as described.

2. A receptacle of the type set forth comprising a cup which embodies flat parallel front and rear walls having curved under edges and a connecting web joined to said edges, conforming to the curvature thereof and forming the bottom and end walls of the cup, the web having a central concave portion and straight end portions which merge with the central portion and which project upwardly therefrom in divergent relation, and an apron which projects rearwardly and upwardly from the upper edge 130

of the rear wall, forming a cup which defines in longitudinal section an arc of a circle having diverging tangent lines, the apron being of rectangular form and being
5 at all points co-extensive in length with the length of the mouth of the cup defined by the upper edges of said front and rear walls and said web, the apron being furthermore permanently joined to the rear wall and having at its ends parallel upturned flanges which extend continuously from the said mouth to the tree upon which
10 the receptacle is secured, the flanges terminating short of the rear edge of the apron whereby corner shoulders which abut against the tree and a projecting portion which is formed as a lip to engage in a kerf in the tree, are provided, the ends of the projecting lip being in alinement with the base line of said flanges, substantially as described.

3. A receptacle of the type set forth comprising a cup which embodies flat parallel front and rear walls having curved under edges and a connecting web joined to said edges, conforming to the curvature thereof, and forming the bottom and end walls of
15 the cup, and an apron which projects rearwardly and upwardly from the upper edge of the rear wall, the apron being of rectangular form and being at all points co-exten-

sive in length with the length of the mouth of the cup defined by the upper edges of said front and rear walls and said web, the apron being furthermore permanently joined to the rear wall and having at its ends parallel upturned flanges which extend continuously from the said mouth to the tree upon which
25 the receptacle is secured, the flanges terminating short of the rear edge of the apron whereby corner shoulders which abut against the tree and a projecting portion which is formed as a lip to engage in a kerf 30 in the tree, are provided, the ends of the projecting lip being in alinement with the base line of said flanges, substantially as described.

In testimony whereof I affix my signature 40 in presence of two witnesses.

JOHN MILLENDER BYRD.
